CHEST FOR FLATWORK IRONER

Oscar W. Johnson, Rochester, N. Y., assignor to
The American Laundry Machinery Company,
Cincinnati, Ohio, a corporation of Ohio

Application September 20, 1930
Serial No. 483,270

2 Claims. (Cl. 68—9)

My invention relates to steam heated beds or chests and particularly chests of the type used in flat work ironers and whose surfaces are polished and engaged by padded rolls forming a part

5 of the ironer, the articles being fed between the rolls and chests in the ironing operation.

It is well-known that in the operation of flat work ironers, steam is supplied to the chest for the purpose of heating them to impart an ironed 10 finish to the goods passing thereover and it necessarily follows that means have been provided for allowing the steam to exhaust from the chest and for removing the water of condensation. However, in the old method of draining these flat 15 work ironer chests or bed members, the drain was taken off at the centre of the chest which has been unsatisfactory in that the lower walls of the chest are inclined at an angle creating a pocket that would fill with condensate from the steam used for heating the chest thereby causing 20 a decrease in the temperature of the chest during the ironing operation.

It is one object of this invention to overcome 25 this objection by providing a means wherein the low point of the chest is carried to the center thereof by means of ports and channels, thus eliminating the pocket, and locating the drain at this low point whereby the chest may be thoroughly drained of any liquid that has condensed 30 from the steam.

Another object of my invention is to provide a steam chest of the above type so designed that not only are certain of the chests reversible and adapted for use with any one of a number of 35 rolls of an ironing machine, but also this new type chest may be inserted as a replacement in machines already in use, but without requiring any serious modifications in the frame, piping, etc.

40 Various other objects of this invention may be seen in the following description and one embodiment thereof may be seen in the accompanying drawings wherein Fig. 1 is a longitudinal section of a flat work ironer and showing a heating chest in section; Fig. 2 is a sectional view showing a chest constructed in accordance with my invention; Fig. 3 is a sectional view taken on the line 3—3 of Fig. 2; Fig. 4 is a sectional fragmentary view taken on the line 4—4 of Fig. 3; Fig. 5 is a 45 plan view showing the two central chests of a flat work ironer, the center portions of each chest being broken away so that both ends of each chest may be shown; Fig. 6 is a vertical section of the chest shown in Fig. 5. This view shows the internal walls in dotted lines and the position of

the drainage passage in each chest; Fig. 7 is a sectional view taken on the line 7—7 of Fig. 6; and Fig. 8 is a sectional view taken on the line 8—8 of Fig. 6.

Referring to the drawings, I have shown one embodiment of my invention as comprising a steam chest for use in conjunction with a flat work ironer which consists of a frame 1 provided with horizontally projecting portions 2 that form a support for steam chests or heated ironing members 3. These supporting portions or shelves of the frame are so arranged, as shown in Figs. 1, 5 and 6, that one shelf supports the adjacent sides of two adjoining chests and the supports or shelves are arranged with a gap therebetween 60 providing room opposite the middle of each chest member for a connection to a drainage or steam inlet pipe, as in the ordinary construction, and the upper wall of each steam chest is concave and adapted to be engaged by an ironing roll 4. Also, 65 the lower surface and floor 5 of each chest is inclined so that an apron 6 will snugly adhere to all of the chests. Such inclination of the floor of each chest causes a channel or pocket to be 70 formed at the low level along one transverse edge, 75 as shown at 7 in Fig. 1 which will ordinarily collect liquid condensed from the steam used in heating the chest.

In accordance with my invention, each of the steam chest members 3 is provided at its ends with 80 outwardly extending feet 8 adapted to rest on the supports or shelves 2 as shown in Fig. 6 and being secured thereto by means of bolts 9, each of the supports or shelves 2 supporting the adjacent 85 ends of two adjoining chest members. Each of the chests is also provided with two drainage 90 chambers 10 located at opposing ends of the interior chamber A and formed by a top wall 11, a side wall 12 having a port 13 therethrough and connecting the interior of the chambers with the interior chamber A of the chest, and a drainage 95 floor 14 that inclines toward the middle of the chest and leads to a passage 15 which, in turn, leads to an inlet or a drain 16 to which a pipe 17 100 may be connected, the pipe serving the purpose of a steam inlet or of carrying away the liquid condensed from the steam within the chest to any desired point. Further, each chamber 10 is provided with an outlet passage 18 normally 105 closed by a plug 19 which provides a further means for draining the chest. The chambers and passages at each side of the interior of each chest are identical, one of these chambers and 110 passages being used as a steam inlet and the

other being used as a steam outlet and as a drain for the liquid condensed from the steam.

One of the features of my invention resides in the fact that certain of the steam chests that go to make up a complete flat work ironer may be reversed and used in conjunction with any one of several of the ironing rolls when constructed in accordance with my invention. As shown in Figs. 5 and 6, the steam chest members 20 and 21 10 may be turned end for end and reversed as to their positions. That is, the chest 20 may be turned end for end and placed in the position occupied by the chest 21 and the chest 21 may be turned end for end and placed in the position occupied by the chest 20. Such reversibility is 15 also true of all other chests located in similar respective positions that go to make up a flat work ironer with the exception of the two end chests which are necessarily special in construction as will be clearly seen in Fig. 1 and are, 20 therefore, not reversible. Such reversibility is particularly advantageous in a flat work ironer embodying a plurality of rolls and chests, for instance six, in that the number of patterns required for making the steam chests is only four 25 instead of the heretofore usual six.

Moreover, by bringing the supply inlet and drain outlet to the middle of the ends of each chest member they are directly opposite the gaps in the shelves 2 and therefore more or less uniformly spaced along the machine. Indeed, such gaps are shown in the drawings in substantially the same positions which they occupy in older machines now in use but equipped with the former type chests, where the drains have been at the middle of the chests half way up the sloping floor with the formation of a condensate pocket. As a result, it is possible to supply these new chest members as replacements for chests already in use, but without any necessity of cutting away or reforming the supporting shelves or other frame parts or of revamping piping or the like.

Referring to the drawings and the preceding description, I have provided a steam chest for a flat work ironer embodying numerous novel and advantageous features. Aside from the highly advantageous feature arising from the reversibility of certain of the chests, a means is provided for draining the liquid of condensation from the steam chests in substantially the center of the chest which is the most convenient in ordi-

nary types of flat work ironers while still eliminating the collection of condensed liquid at the low point of the chest which is along one transverse edge thereof. Thus, it is possible to eliminate the effect of the condensate on the temperature of the chest and to maintain such temperature more nearly uniform. Various other novel and advantageous features will be readily apparent.

What I claim is:

1. In a flatwork ironing machine of the padded roll and heated pad type, a frame, a plurality of padded rolls lying in substantially the same horizontal plane in said frame, a plurality of substantially uniformly spaced supporting shelf members carried by said frame and forming pairs, a plurality of separate hollow bed members having feet resting on said shelf members and straddling the gaps between them, each bed member having an ironing roll cooperating with the upper wall, the lower wall of said bed forming a floor inclined interiorly of the bed member and longitudinally of the machine toward a condensate channel along the low laterally extending edge of the bed member, and a downwardly sloping drainage conduit at each end of each bed member leading from said channel to a point opposite the gap between each pair of shelf members, a hollow housing at each bed end within one of the gaps and communicating with the corresponding conduit and forming a part of the bed member, and steam and return pipes connected to the housings for supplying steam to the bed member and returning the condensate therefrom. 100

2. A chest member for ironing machines, comprising an elongated hollow chambered member provided with an upper concave wall having an ironing surface, said concavity extending longitudinally of said member and being of substantially uniform depth throughout the length of the member, and said hollow member having a lower wall forming a floor inclined downwardly from one longitudinally extending side of the chamber toward a channel at the opposite side thereof, said member being provided at each end with a drainage conduit communicating with said channel and sloping downwardly toward the middle of the chest end, and steam and drainage connections to said conduits at the middle portions of the chest ends. 115

CERTIFICATE OF CORRECTION.

Patent No. 1,929,978.

October 10, 1933.

OSCAR W. JOHNSON.

It is hereby certified that error appears in the printed specification of the above numbered patent requiring correction as follows: Page 2, line 87, claim 1, for "pad" read bed; and that the said Letters Patent should be read with this correction therein that the same may conform to the record of the case in the Patent Office.

Signed and sealed this 5th day of December, A. D. 1933.

F. M. Hopkins
